EDWIN L. GRAUEL, OF CINCINNATI, OHIO

MATCH PACKAGE

Application filed September 19, 1930. Serial No. 483,049.

My invention relates to match packages of a type in which the match is caused to ignite by the act of removal from the package.

It is the object of my invention to provide a simple and effective package for the above purpose. Such a package must be very inexpensive to make and to fill. It must have the ability to closely hold a series of matches irrespective of variations in size of match, both in thickness, shape and length. Further, the arrangement should be such that the match package itself is suitable as a filler in a holder which supplies tension on the exit end of the package so as to pinch the match during its withdrawal.

The holder, which forms a feature of my invention, must also be simple of construction, must supply a grip at the exit portion of the match passage, but must not bite into the matches of itself.

The above requirements are taken care of in my invention, of which a typical example is shown in the drawings and will be fully described, and the novelty of the invention so illustrated will be set forth in the appended claims.

In the drawings:—

Figure 1 is a plan view of the blank for the match fold.

Figure 2 is a perspective of the match fold bent into shape when laid over a group of matches.

Figure 3 is a plan view of the blank for the jacket.

Figure 4 is a perspective of the jacket folded and glued and ready to slip over the match fold.

Figure 5 is a perspective of a suitable holder, into which the packages of matches can be inserted.

Figure 6 is a perspective section enlarged, of the holder and filler combined.

Figure 7 is a perspective of a plural fold in a single jacket.

Figure 8 is a blank from which it can be formed.

The blank 1 is formed of a piece of fairly heavy board, on the ends of which are printed bands 2 of suitable fulminate or striking substance for the matches. The blank is pref-

erably tapered in at the center and double scored to form a squared fold at the middle. When filled with a row of matches, inserted with the heads down and the ends projecting, this blank forms a fold 3, which has been termed the match fold.

The blank 4 is formed of a piece of tough paper, the wings 5 of which are folded over and glued to form the tapering sleeve 6, which has been termed the jacket.

In making up the match package, the matches are placed in the fold blank which is then folded and the jacket thrust over it. The effect of the taper of the jacket is to grip the match fold and matches tightly.

It will be noted of this package, that the same package will serve for matches of various lengths, since the longer ones will simply project further. The matches must only be long enough to project sufficiently to be gripped by the fingers and jerked from the package. It will be noted further that the matches may vary in diameter of stick, and yet the jacket will grip them firmly, and also the overall length of the matches may vary and still the jacket will grip the fold and hold together the assembly.

The match package formed of the match fold and the jacket can be used by itself, although this is not particularly desirable. Using the match package by itself, the user will grasp a match in his fingers and, holding the top edges of the package, will remove it. The act of jerking out the match will bring its head between the fulminate coating at the lips of the fold, and the match will ignite during the act of withdrawal and burst into flame after it leaves the package.

The match package consisting of fold and jacket filled with matches can be made up and assembled as cheaply as a paper packet of matches, and is thinner in the pocket.

The package adapts itself most excellently as a filler for a holder. The holder may take the simple form of a piece of metal folded as at 7, and with its lips curled in slightly at 8. The match package is slipped laterally into the holder, with the upper edges of the fold lying under the curled lips. The lips are not curled far enough to overlie the

inner faces of the fold, although they may be given an additional upward and inward bend 8a, which will prevent re-insertion of a partially withdrawn match. The holder is 5 slightly expanded by the act of inserting the match package, and accordingly forces the lips of the match fold together, thus supplying sufficient friction against the head of a match when it is withdrawn so as to cause it 10 to ignite, without the necessity of the user pinching the top of the holder together.

It will be apparent that the jacket of the match fold can bear advertising matter, while the holder itself may be enameled and 15 styled to suit the taste of the user; or built as part of an ash tray or other fixture. Its thinness makes it attractive, and fits it for the vest pocket and the woman's vanity bag. Very much thinner matches can be used be- 20 cause the strain of striking the match is only exerted longitudinally of the stick.

Of course the holder could also bear advertising matter and be sold as a novelty, but the arrangement is such that the advertising 25 can be done on the jackets, without distasteful effect to the user of the matches.

When a double or triple row of matches is required, the fold itself may be made with lateral flaps. Thus I have shown in Figure 30 8 a blank for a double match fold. The tabs 10 and 11 are the main or outer folds, and the tab 12 folds in between them and acts as a partition between two rows of matches. Fulminate, as shown, is placed along the 35 zones of the blank which will lie at the lips of the fold, and the partition fold will have fulminate both front and back. The jacket for such a fold will naturally be of a size to slide over and grip the double fold.

40 I have described the embodiment of my invention which is reduced to the simplest form, and variants will occur to those skilled in the art, which will not depart from the spirit of my invention as expressed in the 45 ensuing claims.

Having thus described my invention, what I claim as new and desire to secure by Letters Patents, is:—

50 1. A match package comprising a tapered folder within which matches are arranged with their ends projecting; a tapered jacket embracing the folder and holding it closed, said tapered folder being insertable through the larger end opening of said jacket, and striking substance for the heads of the 55 matches located at the lips of the folder.

60 2. A tapered match package comprising a tapered folder within which matches are arranged with their ends projecting; a tapered jacket embracing the folder and holding it closed, and striking substance for the heads of the matches located at the lips of the folder, said tapered folder and tapered 65 jacket being slideable with respect to each

other to positions of snug fit irrespective of the number of matches in said folder.

3. A tapered match package comprising a tapered folder within which matches are arranged with their ends projecting, an open-ended, tapered jacket embracing the folder and holding it closed, and striking substance for the heads of the matches located at the lips of the folder, said folder and contained matches being insertable into said jacket 75 through the larger end opening thereof.

4. A tapered match package comprising a tapered folder within which matches are arranged with their ends projecting, an open-ended, tapered jacket embracing the folder and holding it closed, and striking substance for the heads of the matches located at the lips of the folder, said jacket and said folder having a substantial taper of the same angularity, whereby said jacket and said folder are slideable with respect to each other to positions of snug fit irrespective of the withdrawal of matches from said folder.

5. A match package comprising a tapered folder within which matches are arranged with their ends projecting, a tapered jacket embracing the folder and holding it closed, said tapered folder being insertable through the larger end opening of said jacket, and striking substance for the heads of the matches located at the lips of the folder, and a holding member comprising oppositely disposed spring leaves arranged for sidewise insertion of said package and disposed so as to exert pressure on the faces of said package 90 adjacent the lips of said folder.

6. A match package comprising a tapered folder within which matches are arranged with their ends projecting, a tapered jacket embracing the folder and holding it closed, said tapered folder being insertable through the larger end opening of said jacket, and striking substance for the heads of the matches located at the lips of the folder, and a holding member comprising oppositely disposed spring leaves arranged for sidewise insertion of said package and disposed so as to exert pressure on the faces of said package 100 adjacent the lips of said folder, said spring leaves having portions turned over the ends 110 of said package to prevent endwise withdrawal thereof.

7. A match package comprising a tapered folder within which matches are arranged with their ends projecting, a tapered jacket embracing the folder and holding it closed, said tapered folder being insertable through the larger end opening of said jacket, and striking substance for the heads of the matches located at the lips of the folder, and a holding member comprising oppositely disposed spring leaves arranged for sidewise insertion of said package and disposed so as to exert pressure on the faces of said package 120 adjacent the lips of said folder, said spring 125 leaves having portions turned over the ends 130 of said package to prevent endwise withdrawal thereof.
